FIG. 3 is a front elevational view thereof;

FIG. 4 is a right side elevational view thereof, the left side elevational view thereof being a mirror image;

FIG. 5 is a rear elevational view thereof;

FIG. 6 is a bottom plan view thereof;

FIG. 7 is a top, front, and right side isometric view of a second embodiment of the spray actuator;

FIG. 8 is a top plan view of the second embodiment;

FIG. 9 is a front elevational view of the second embodiment;

FIG. 10 is a right side elevational view of the second embodiment, the left side elevational view thereof being a mirror image;

FIG. 11 is a rear elevational view of the second embodiment;

FIG. 12 is a bottom plan view of the second embodiment;

FIG. 13 is a top, front, and right side isometric view of a third embodiment of the spray actuator;

FIG. 14 is a top plan view of the third embodiment;

FIG. 15 is a front elevational view of the third embodiment;

FIG. 16 is a right side elevational view of the third embodiment, the left side elevational view thereof being a mirror image;

FIG. 17 is a rear elevational view of the third embodiment;

FIG. 18 is a bottom plan view of the third embodiment;

FIG. 19 is a top, front, and right side isometric view of a fourth embodiment of the spray actuator;

FIG. 20 is a top plan view of the fourth embodiment;

FIG. 21 is a front elevational view of the fourth embodiment;

(Continued)

FIG. 22 is a right side elevational view of the fourth embodiment, the left side elevational view thereof being a mirror image;

FIG. 23 is a rear elevational view of the fourth embodiment; and,

FIG. 24 is a bottom plan view of the fourth embodiment. In the drawings, the evenly-spaced broken lines represent unclaimed subject matter.
